Primary Examiner — Rebecca Tsehay(74) *Attorney, Agent, or Firm* — Kirk A. Buhler; Buhler & Associates Patenting(57) **CLAIM**

The ornamental design for a hookah, as shown and described.

DESCRIPTION

FIG. 1 is a top perspective view of hookah, showing our new design;

FIG. 2 is a front elevation view thereof;

FIG. 3 is a rear elevation view thereof;

FIG. 4 is a left side elevation view thereof;

FIG. 5 is a right-side elevation view thereof;

FIG. 6 is a top plan view thereof; and,

FIG. 7 is a bottom view thereof.

The broken lines depict portions of the hookah that form no part of the claimed design.
